CLAIM

The ornamental design for a display container for periodicals, as shown and described.

DESCRIPTION

FIG. 1 is a perspective view of the display container in its closed state;

FIG. 2 is a front view of the display container corresponding to FIG. 1;

FIG. 3 is a right side view of the display container decorative cover corresponding to FIG. 1, with the left side view being a mirror image of FIG. 3;

FIG. 4 is a top view of the display container corresponding to FIG. 1;

FIG. 5 is a rear view of the display container corresponding to FIG. 1;

FIG. 6 is a bottom view of the display container corresponding to FIG. 1;

FIG. 7 is a perspective view of the display container in its open state;

FIG. 8 front view of the display container corresponding to FIG. 7;

FIG. 9 is a right side view of the display container decorative cover corresponding to FIG. 7, with the left side view being a mirror image of FIG. 9;

FIG. 10 is a rear view of the display container corresponding to FIG. 7;

FIG. 11 is a top view of the display container corresponding to FIG. 7;

FIG. 12 is a bottom view of the display container corresponding to FIG. 7;

FIG. 13 is a perspective view of an alternative embodiment of the display container for storage in a three-ring binder in its closed state;

FIG. 14 is a front view of the display container corresponding to FIG. 13;

FIG. 15 is a right side view of the display container decorative cover corresponding to FIG. 13, with the left side view being a mirror image of FIG. 15;

FIG. 16 is a top view of the display container corresponding to FIG. 13;

FIG. 17 is a rear view of the display container corresponding to FIG. 13;

FIG. 18 is a bottom view of the display container corresponding to FIG. 13;

FIG. 19 is a perspective view of the display container shown in FIG. 13 in its open state;

FIG. 20 front view of the display container corresponding to FIG. 19;

FIG. 21 is a right side view of the display container decorative cover corresponding to FIG. 19, with the left side view being a mirror image of FIG. 21;

FIG. 22 is a rear view of the display container corresponding to FIG. 19;

FIG. 23 is a top view of the display container corresponding to FIG. 19;

FIG. 24 is a bottom view of the display container corresponding to FIG. 19; and,

FIG. 25 is a vertical cross-sectional view of the display container.
